UNITED STATES PATENT OFFICE.

FERDINAND PAUL AUGUST WEYLER AND HORACE FREED, OF PHILADELPHIA,
PENNSYLVANIA.

ELECTRICAL POLICE SIGNAL.

Application filed September 20, 1926. Serial No. 136,630.

The present device enables a central police station to call up a single or simultaneously several or all signal boxes; to use in calling different signalling instrumentalities, to communicate information either singly at an individual box or simultaneously at a number of boxes, and to reproduce the messages either secretly to the hearer or by broadcasting it, from one or several or all the boxes by a loud speaking instrumentality. It consists, essentially, of a suitable centerphone system, that is a system in which a central telephone station is connected to several outlying boxes which it can call individually or collectively, combined with various instrumentalities in the central station and at the boxes. By their use an ordinary centerphone system is enabled, commonly, though not necessarily, without a change in the street connections, to give a light signal, or a loud speaking effect at any box, or several, or all of them as well as to serve the ordinary purposes of mutual communication between the station and the boxes, which are not interfered with by the inclusion of these instrumentalities in the system, and the box is not interfered with as a transmitting instrumentality by their use more than it is by the use of the ordinary calling from the station. It also contains means for notifying the station that a person at the box wishes to get into communication, which will operate even during the signalling or broadcasting of loud speaking, so that a person at the box can always be assured of his ability to communicate to the station his need to communicate with it.

In describing my device, I have illustrated the centerphone system as the No. 12 A. of the Connecticut Telegraph and Telephone Company, a very generally used centerphone system.

Fig. 1 is a view of a suitable form of box. Fig. 2 is a diagram of a system, equipped with the instrumentalities of my device. Fig. 3 is a detail of an instrumentality for automatically repeating signals.

The centerphone system illustrated has a 2 wire talking circuit, common to all boxes, and an individual ringing circuit for each box, using in the later mentioned circuit for each box, a single individual wire and a wire common to all circuits, and using for the ringing circuit ringing the bell at the station this common return wire and one of the wires of

the common talking circuit. It has the ringing battery, 60, and the talking battery, 61, and the station and boxes are furnished with the ordinary switches, (usually jack plugs), by which the individual ringing circuit to each box is made and broken. This or a similar system is used at the present time in many police box systems. We have combined with such a centerphone system, not necessarily precisely as illustrated but having its general character, instrumentalities that enlarge its capacities. We combine it, at the station, with switches and batteries of higher potential, and at the boxes with instrumentalities, most advantageously in the form of relays, that when a current of higher potential shall pass through the talking circuit will divert the course of the current of the talking circuit so that it will flow through a loud speaker, and, when a current of higher potential passes through the ringing (calling) circuit, a lighting current is thrown on at the box and a signal lamp lighted there and combine these instrumentalities with instrumentalities at the station that enable the calling signals to be given at one or simultaneously several of these boxes, and to be given continuously, intermittently at the will of the signaller or repeated rhythmically and automatically.

Describing now the best form of our device of which we are at present aware:—A represents a station, and B and C two of the boxes, 15 a common return wire of the circuits for ringing the boxes, 11 and 12 are individual calling wires to boxes B and C respectively, 2 is a station telephone hook switch contacting when the receiver is lifted with the contact, 3, that is in electrical connection with the inductance, 4, and through the lead, 1, with the wire, 15, of the common talking circuit. The hook, 2, is also in constant electrical connection with the other wire, 14, of the talking circuit. The ringing bells, 6, 6, at the station A are connected by a lead, 9, with the wire, 13, but the lead, 10, instead of being carried directly to the battery, 60, passes to it through the lead, 16, and switch, 108, and lead, 17. A lead, 8, connects electrically the station bell circuit through the general conductor, 7, and the switches, 52, 53, 54, 55, and 56, (up to the number of boxes) with the leads leading to the individual box ringing circuits. The leads, 28, and 29, connected to the wires, 11, and 12, only, are shown. The boxes B and C have the ringing

circuits comprising bells, 43, 43, and leads, 41, 41, in connection with a common return wire to the battery, (formed by one of the wires, 14, of the talking circuit in the centerphone system illustrated) and the leads, 40, 40, connected to the individual signal wires of the box; wire, 11, of box B and wire, 12, of box C. The talking circuit includes the leads, 41, and 105. These elements are not new (except as above noted) and the novelty of our device lies in combining the instrumentalities hereinafter described into this general class of circuits.

The lead, 40, at the box B, has the relay, 93, connected in parallel with it, the resistance, 67, being also included in the shunt circuit, 65, if necessary. This relay has an armature, 69, that, when a current of sufficiently high potential has energized the relay, 93, closes the circuit through a lead, 110, and containing a source of electrical energy, 63, and a lamp, 64. At the box, C the armature, 92, the shunt circuit, 89, the resistance, 95, lamp, 164, and the circuit leads, 80, and 81, including the source of electrical energy, 63, are located and operate in like manner. The box B likewise has the relay, 95, in a shunt circuit, 97, which contains also a resistance, 111, if required to supplement the resistance of the relay. The lead, 98, is connected through the armature, 101, when the relay is inactive, with the lead, 99, that is connected to the lead, 105, leading to the box telephone receiver, and, when a current of high enough potential passes through the lead, 98, to energize it, the loud speaker, 94. As the loud speaker will be used when the telephone hook of the box is down, it is connected to the lead, 41, by the lead, 100. The loud speaker battery, 125, is included in a circuit, 122, that is closed by the armature, 120, of the relay, 121, set in a relay circuit, 123, in parallel with the lead, 98. The switch, 103, closes the circuit through the lead, 102, in electrical connection with the lead, 41, and including the bells, 6, 6, at the station, and although the loud speaker or the regular speaking circuit be in operation will ring them notifying the station that a person is at a box desirous of communicating. This switch is shown in Fig. 1 placed outside the box, for the convenience of operation for an officer encumbered with a prisoner.

The battery, 60, is an ordinary ringing battery, but instead of having the pole connected directly to the wire, 14, has the lead, 18, from the negative pole, carried to a contact, 72, of a switch, 108, that has the other pole (a fixed pole) at the terminal, 76, from which a lead, 22, runs connecting it with the lead, 14. The battery, 61, is a talking battery that instead of having the positive pole directly connected to the wire, 15, has a lead, 20, connecting it with a pole, 150, of the switch, 109, and its negative pole connected

to the terminal, 59, of the switch, 109, by the lead, 26. The switches, 108, and 109, are double throw double pole switches preferably.

Having above described the ringing and talking circuits, as modified for the particular purposes of our improvement, and also the relays and circuits in the typical preferred form of box, we will now describe the instrumentalities for operating the boxes 75 from the station. The signalling light is operated by increasing the electro-motive force of the current passing through the conductor, 40, so that its potential will be sufficient to make it overcome the resistance in 80 the shunt circuit, 65, and energize the relay, 93. This we do in practice by replacing in the circuit the battery, 60, by the battery, 62, which is of much higher potential than the battery, 60.

In practice, we connect a pole of this battery with the contact, 78, of the switch, 108, and the other pole of the battery, 62, with the terminal, 57, of the switch, 108. The turning of the switch will leave the circuit between the terminals, 71, and 75, through the station and boxes the same, but the battery, 62, will replace the battery, 60, in the circuit.

The inclusion of a battery, 66, of higher potential than the battery, 61, in the talking 95 circuit can be similarly accomplished by connecting one of its poles through a lead, 58, with the terminal, 57, of the switch, 109, and the other of this battery's poles through a lead, 30, with the terminal, 153, of this 100 switch. The turning of the switch, 108 will leave the talking circuit, through the station unchanged, and the talking circuit through the typical preferred form of box 105 unaltered, except where diverted by the relay, 95, the battery, 66, being substituted for the battery, 61. The battery, 66, has sufficient potential to cause a current of sufficient electro-motive force to flow in the lead, 20, to overcome the resistance of the shunt circuits, 97, and 98, and energize the relays, 121, and 95, closing the circuit through the battery, 125, and loud speaker, 94, and through a lead, 96, the loud speaker, 94, and the lead, 100, to the lead, 41.

The instrumentalities enable the station to send out signals to a single station, and to broadcast from a loud speaker simultaneously, from a number of boxes. We have also added to these a multiple pole switch, 51, 120 which is connected by leads, as 37, 37, to the individual signaling lines of a number of boxes, and an automatic signalling device such as a rotary drum, 50, to the axis of which is connected the wire, 31, switch, 70, and wire, 125 33. The brushes, 91, and 92, and leads, 35, and 34, are connected electrically to their individual signalling wires, 28, and 29.

The box C has the loud speaker somewhat differently arranged, so that the loud 130

speaker operates only when the telephone receiver is off the hook. The leads, 84, and 85, form a shunt circuit including the relay, 101, and the resistance, 90, in parallel with the circuit through the telephone receiver. The wires, 93, and 86, through which, alternately, the circuit is made by the vibrations of the armature, 941, also both are connected electrically to the wire, 105, the lead, 87, is in electrical connection with both the armature, 941, and the wire, 15, the wire, 105, is out of circuit until the hook is lifted, so the loud speaker at box C will not operate until the light or bell is answered. The operation of the loud speaker booster battery and its circuit is not illustrated in connection with the loud speaker, 88, but is the same as is illustrated at box C.

The switches, 71, 51, the automatic repeater, 50, and the switches, 108, and 109, can all be placed at a single switch board at the station. By manipulation of the switches the various effects desired can be produced. Portions of these effects can be produced successively, or some completely omitted. For instance, the circuits through the plugs, 52, and 55, alone can be made, ringing two boxes only. Then the battery, 62, can be thrown in by turning the switch, 108, and then the loud speakers in boxes of the B type thrown on all over the district by turning the switch, 109.

The circuit through the batteries can be shifted with single pole switches, if desired, but this is not as desirable as the arrangement illustrated, and many changes can be made in the details of the circuits without departing from our invention.

We claim:—

1. In a police alarm system, having a central station, and a series of outlying boxes which are callable and communicable with both individually and collectively from the central station, the combination of a signal light and its circuit placed at each box, a relay set in parallel with the ringing circuit at each of these boxes, and operative when the circuit is traversed by a current of higher electro-motive force and inoperative when a current of less electro-motive force traverses the ringing circuit of the box and means operatable from the station for increasing

the potential of the sources of electrical current traversing these ringing circuits, and a circuit including the signal light, and a source of electrical lighting energy and the armatures of said relays and closed by these relays.

2. The device as defined in claim 1 with the additional element:—"and means for automatically giving said signals in a fixed repetitive order".

3. The device as defined in claim 1, with the following additional element:—"and a multiple pole switch for throwing on simultaneously plural circuits through a number of outlying boxes".

4. In a police alarm system having a central station, and a series of outlying boxes, which are callable and communicable with both individually and collectively from the central station, of a loud speaker placed in circuit at each of the boxes in the district, a relay in shunt in the talking circuit at these boxes operative when a current of high or electro-motive force traverses the circuit and inoperative when a current of lower electro-motive force traverses it, a circuit through the loud speaker including the armature of the relay and closed when the current of higher electro-motive force traverses the talking circuit, or source of electrical energy, and means at the station for increasing the potential of this source of electrical energy.

5. The device as defined in claim 4 with the additional element:—"and a booster battery for the loud speaker, and a relay operative when the current of higher electro-motive force traverses the talking circuit, and a circuit containing the booster battery, the loud speaker, and the armature of said latter relay, and closed when the said relay is inoperative."

6. The device as defined in claim 4, with the following additional element:—"the shunt circuit containing the relay being connected across the leads electrically connected to the talking wires of the center telephone system and the circuit containing the loud speaker being also connected across the same wires."

FERDINAND PAUL AUG. WEYLER.
HORACE FREED.
